UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

HIGH-FREQUENCY TRANSMISSION AND RECEPTION.

Application filed December 31, 1923. Serial No. 683,630.

This invention relates to radio transmission and reception systems, and more particularly to systems using the same antenna for both transmitting and receiving.

5 An object of this invention is to provide for changing from a two-way radio system for transmitting and receiving in accordance with the method in which local oscillations, used to produce an intermediate frequency, 10 in duplex receiving, are supplied by the transmitter to a two-way system operating in accordance with the method in which the local oscillations are supplied by a local oscillator.

15 A feature of the invention relates to arrangements whereby an operator may switch from a full duplex radio system to a push-button or antenna-switch two-way system which systems comprise practically the same 20 electrical elements.

A feature of the invention relates to a highly selective circuit arrangement for amplifying incoming waves and suppressing a particular frequency of undesired waves.

25 For the purpose of illustrating an operative system embodying the invention it will be hereinafter described as applied to a system in which use is made of the same antenna for both transmission and reception. A

30 particular embodiment of the invention comprises a transmission circuit, a receiving circuit and an antenna. The transmitting circuit has included therein a source of speech waves, a source of high frequency oscillations and means for modulating the high frequency waves by the speech waves to produce a wave for radiating. The receiving circuit may be one comprising selective amplifying devices, a high frequency detector

35 and a source of local oscillations, an intermediate frequency amplifier, an intermediate frequency detector and receiver, the circuit operating on the basis of double detection; or one comprising selective amplifying

40 devices, detector and receiver for single detection, with an alternative circuit arrangement for increasing the range of selectivity. Consideration of the following description will suggest, to those skilled in the art, other 45 objects and advantages of the invention.

In the drawings, Fig. 1 represents a circuit diagram embodying the transmitter portion of the system.

50 Fig. 2 represents a form of receiving system embodying double detection.

Fig. 3 represents a form of receiving system embodying single detection.

Fig. 3^a represents a modification of the high frequency amplifier and selecting circuit of the receiving system shown in Fig. 3. 60

Fig. 4 is a graphic diagram showing the fluctuation of amplitude with respect to frequency in a selective circuit such as shown in Fig. 3.

Figs. 1 and 2 together illustrate a complete transmitting and receiving system, Fig. 1 showing the transmitter and Fig. 2 the receiver.

In Fig. 1, waves from a source of speech frequency waves 1 are impressed by a transformer 2 upon the speech frequency amplifier 3.

Vacuum tube 4 represents a speech frequency modulator or variable impedance device. Iron core choke coil 5 is connected in the plate circuit of tube 3 and 6 is a stopping 70 condenser for preventing direct current from being impressed upon the grid of tube 4.

A resistance 7 is located in the positive plate supply lead from source of direct current 14 to reduce the voltage impressed upon the 80 lower power tube 3. The circuit 8 comprising resistance and inductance acts as a stabilizing circuit to establish the input impedance of the tube 4 at a proper value and provide a low resistance path between 85 grid and filament.

High frequency choke coil 9, in the plate circuit of tube 4, offers impedance to high frequency waves and therefore acts as a high frequency choke coil. Tube 10, in cooperation with tuned circuit 90 16, supplies oscillations which are modulated by the amplified voice frequency waves. Tube 11 serves as a high frequency amplifier operating in accordance with the constant current method of modulating. Iron core 95 choke coil 12 is the speech frequency choke coil in the constant current modulating system.

A source of alternating current 13 supplies energy to the filaments of the tubes 100 3, 4, 10 and 11. Circuit 19 acts as an average filament potential regulator, providing a potential point corresponding to the mid-point of the filaments. The capacities 30 by-pass high frequencies around the circuit 19.

Source of direct current 14 supplies energy to the plates of the tubes 3, 4, 10 and 11. The armature fluctuations of the source 14 are suppressed by means of the filter 31. 110

which comprises a plurality of iron core choke coils and capacities.

High frequency oscillations to beat with incoming waves in the receiving circuit are supplied by the leads 32 and 33 which are inductively connected to the output of the oscillator 10 by means of inductance coil 15.

Polarizing battery 17 is located in the grid circuit of tube 3, while battery 18 is similarly located in the grid circuit of tube 4. Choke coil 20 provides a D. C. path for current from the source 14 to the plate circuit of tube 10 and compels high frequency plate currents of the tube 10 to pass through the tuned circuit 16. Choke coils 21, in cooperation with capacity 22, act as a filter to keep high frequency waves from entering the low frequency apparatus.

Capacity 23 with inductance 27, offers low impedance for high frequency waves, and keeps the high voltage direct current from reaching the antenna. Capacity 34 is located in the antenna circuit to decrease the total antenna capacity. The circuit 29, comprising resistance 25 and capacity 26, in combination with inductance 24 acts as a grid leak path for the grid of tube 11. Grounded air core inductance 27 has a plurality of taps so that the anode of tube 11 may be connected to a variable portion of the inductance of the coil.

The outgoing waves pass through the inductances 28, capacity 34, portion 35 of contact arm 38 to the antenna 39 from which they are radiated. Portions 35, 36 and 37 of contact arm 38 are insulated from each other. Trap circuit 40 comprising the inductance 41 and capacity 42 tends to prevent the passage of carrier oscillations of the frequency used in transmitting, but a sufficient amount passes through to be used to beat with incoming waves in one method of receiving. Switch 43 is of the double throw type making contact either with slots 44 or 45.

Relay 46 is used to throw the contact arm 38 either to the right or left by means of push-button 50 and grounded source of direct current 47. When contact arm 38 is to the left, potential from source 14 is fed to the plates of tubes 4, 10 and 11, through leads 51 and 52 and portion 37 of the contact arm. No potential is supplied to these plate circuits when the arm is to the right and, to prevent sparking on the opening of the contacts between 37 and leads 51 and 52, condenser 49 is connected between leads 52 and 53.

Incoming waves before reaching the detector pass through tuned circuit 54 comprising inductance 55 and variable capacity 56. Coil 57 acts as the secondary of a transformer, the primary of which is coil 55, and in cooperation with capacity 58 of Fig. 2 constitutes a tuned circuit. The tuned cir-

cuit comprising inductance 57 and capacity 58 and the circuit 54 are denoted by B_2 and B_1 , respectively. They function as selective circuits for selecting incoming waves of a specific frequency and for discriminating against waves of any other frequencies.

In Fig. 2, selective amplifier 59 amplifies the incoming waves selected by the tuned circuits B_1 and B_2 . Tuned circuit A comprising inductance 60 and capacity 61 discriminates against oscillations of the frequency used in transmitting. Capacity 62, and inductance 63 comprise another tuned circuit B_3 acting in cooperation with a similar circuit B_4 comprising inductances 64 and 65 to further select incoming waves of the frequency desired for detection.

In double detection methods of receiving, local oscillations must be supplied to the detector to beat with incoming waves. For this purpose, local oscillator 67 supplies oscillations to the high frequency detector 74 through lead 68, switch 72, induction coil 69 and inductance 64 of tuned circuit B_4 .

For another method of double detection, local oscillations are supplied by the transmitting system by means of leads 32 and 33, regulating device 70, which regulates the flow of high frequency waves to the detector tube, switch 71, induction coil 66, and inductance 64 of tuned circuit B_4 . From the last mentioned tuned circuit, B_4 , incoming waves are impressed upon the high frequency detector 74 along with locally supplied oscillations. These oscillations and the incoming waves are combined to produce an intermediate frequency wave which passes through tuned circuit 84 comprising inductance 76 and capacity 75, tuned circuit 85 comprising inductance 77 and capacity 78 to the intermediate frequency amplifier 79. The inductance coils 76 and 77 act as the primary and secondary of a transformer respectively.

The amplified waves are impressed upon intermediate frequency detector 82 through transformer 80 and the resultant audible note is detected in receiver 83. The circuit 73 comprising resistance and capacity acts as a grid leak for tube 74, while similar circuit 81 acts in a like manner for tube 82. When local oscillations are supplied by the transmission system, switch 71 is closed and 72 opened. Likewise, when local oscillations are supplied by local oscillator 67, switch 72 is closed while 71 is opened.

Fig. 3 represents a modified form of the receiving system embodying single detection. As in Fig. 2 condenser 58 acts in cooperation with inductance 57 to complete a tuned selective circuit B_2 . Selective amplifier 59 amplifies the high frequency waves selected by tuned circuit B_2 and they pass through tuned circuit A₁ comprising inductances 60 and 61. This circuit A₁ discriminates

against the carrier frequency used in transmitting.

Tuned circuit B_3 comprising inductance 63 and capacity 62 and tuned circuit B_4 further select the incoming waves to be detected. The coils of the two circuits act as a transformer. The amplified waves selected in this manner are further amplified by selective amplifier 86.

10 To prevent oscillations of the frequency used in transmitting from reaching the detector, another tuned circuit A_2 comprising inductance 87 and capacity 88 is placed in the output circuit of amplifier 86. Tuned circuit B_5 comprising capacity 89 and inductance 90, and similar circuit B_6 comprising inductance 91 and capacity 92 still further determine the frequency to be detected.

20 The selected waves are next impressed upon the detector 94 and the detected audible signal current is supplied to the receiver 95. Circuit 93 comprising resistance and capacity acts as a grid leak for 25 tube 94.

Fig. 3^a represents a modified circuit arrangement which may be substituted for that portion of the circuit of Fig. 3 between the dotted lines X—X and Y—Y. Inductance coil 99 is constructed with a number of taps which cause the inductance of the coil to be variable and, in cooperation with capacity 100, makes up a tuned circuit. Inductance 101, in connection with capacity 102, forms another tuned circuit, the purpose of which is to discriminate against waves of the transmitting carrier frequency. The tuned circuit, including capacity 103 and inductance 104, coupled to 40 the circuit including capacity 105 and inductance 106, acts in a manner similar to circuits B_1 , shown in Fig. 1 and B_2 , B_3 , B_4 , B_5 and B_6 in Fig. 3. By means of this arrangement, it is possible to provide a high 45 degree of selectivity for the incoming carrier waves of the frequency desired for detection and to discriminate effectively against the transmitted carrier waves.

Fig. 4 represents the manner in which the 50 amplitude varies with respect to frequency at the transmitting and receiving frequency. At the frequency transmission i. e. 650 kilocycles the amplitude is practically zero and at frequency of reception i. e. 700 kilocycles 55 the amplitude reaches a maximum.

Operation.—In one method of operation employing double detection, the switch 43 makes contact with slots 44, the trap circuit 40 is cut in and spring 48 causes bar 38 60 to make contact to the left both for transmitting and receiving. Voice frequency waves from source 1 are amplified by amplifier 3, varied by variable impedance device 4, thereby modulating high frequency oscillations from oscillator 10 and amplified

by high frequency amplifier 11. The high frequency amplified waves then pass through inductances 27 and 28 and capacity 34 to the aerial 39 from which they are radiated. A part of the transmitting carrier oscillations pass through trap circuit 40 to the receiving circuit where they are used to beat with the incoming waves.

Incoming waves are received by antenna 39, passed through portion 35 of contact bar 38, through condenser 34, upper slot 44, switch 43, trap circuit 40 and a portion 36 of a bar 38 to the two tuned circuits B_1 and B_2 . These circuits select the frequency desired for detection and exclude all others.

80 The selected waves are then amplified by amplifier 59 and pass through tuned circuit A which discriminates against waves of the carrier frequency used in transmitting. They then pass through a second set of 85 tuned circuits B_3 and B_4 , whose design and purpose are the same as circuits B_1 and B_2 , previously described.

At this point, there is very little of the 90 transmission carrier frequency waves, because of it having been largely excluded by the circuit A. An amount of carrier frequency energy sufficient to combine with incoming waves to produce an intermediate frequency wave, is supplied from oscillator 10 through the leads 32 and 33, regulating device 70, and induction coil 66, which acts as a primary of a transformer the secondary of which is coil 64. Waves of both frequencies are then impressed on a high frequency detector 74 and an intermediate frequency produced. For example, it may be assumed that transmitting is carried out at 600,000 cycles and receiving at 650,000 95 cycles. The resultant intermediate frequency would be 50,000 cycles. Intermediate frequency waves pass through two tuned circuits 84 and 85, the induction coils of which act as a transformer, to the intermediate frequency amplifier 79, where they 100 are amplified. The amplified waves then pass through transformer 80 and are impressed upon intermediate frequency detector 82. The resultant audible frequency current is supplied to receiver 83.

110 In a second method, also employing double detection, the switch 43 is thrown to the right, to make contact with slots 45 and thereby complete the circuit of the relay 46 through push button 50. While receiving, the circuit through push button 50 is closed, energizing relay 46 and keeping contact bar 38 to the right. For transmitting, the circuit through push button 50 is opened, de-energizing the relay 46, and causing bar 38 115 to be thrown to the left by spring 48. Modulated speech waves are produced and radiated in a manner similar to that described in the previous method with the exception that trap circuit 40 is cut out. Incoming 120 125 130

waves pass through portion 35 of the bar 38, through tuned circuit 34 and the rest of the system in the same manner as described before with the exception that switch 71 is opened, 72 is closed, and local oscillations to beat with the incoming waves are supplied by local oscillator 67 through the leads 68, switch 72 and inductance coils 69 and 64.

Still another method of receiving, employing single detection, may be used in connection with the last described method of transmission. As before, for receiving, the circuit through push button 50 is closed, energizing the relay 46 and throwing bar 38 to the right. Incoming waves are received by antenna 39 pass through portion 35 of the contact bar 38, tuned circuit 54 or B₁, tuned circuit B₂, both of which are tuned to pass only waves of the frequency desired for detection, selective amplifier 59 which amplifies the selected waves, circuit A₁ tuned to discriminate against waves of the carrier frequency used in transmitting, tuned circuits B₃ and B₄ which further select the desired waves, and selective amplifier 86, which further amplifies the selected waves. These waves then pass through the circuit A₂ which functions in a manner similar to A₁, tuned circuits B₅ and B₆ which finally select the waves to be detected. They are then impressed upon detector 94 and the resultant audible frequency current is supplied to the receiver 95.

The alternative arrangement represented in 3^a is used to obtain a greater degree of selectivity by means of the variable tuned circuit comprising capacity 100 and inductance 99, inductance 99 being provided with a plurality of taps. Waves to be detected can be more effectively selected than by the method described in connection with Fig. 3.

The present invention is not limited to the illustrated embodiments but may be embodied in other constructions within the scope of the following claims.

What is claimed is:

1. In a radio system comprising a transmitter circuit, a receiver circuit, including tuning elements, and an antenna, a switch adapted to convert said system from one in which the transmitter and receiver are simultaneously connected to the antenna and in which incoming waves and waves of the carrier frequency used in transmitting are combined to form a wave of intermediate frequency for double detection to a double detection system in which the transmitter and receiver are alternately connected to said antenna under the direct control of a push button.

2. In a radio system comprising a transmitter circuit, a receiver circuit, including tuning elements, and an antenna, a switch adapted to convert said system from one in

which the transmitter and receiver are simultaneously connected to said antenna and in which incoming waves and waves of the carrier frequency used in transmitting are combined to form a wave of intermediate frequency for double detection to a system in which the transmitter and receiver are alternately connected to the antenna under the control of a manually operable element operated by the operator.

3. A radio system comprising an antenna, a transmitter circuit, a receiver circuit, a switch for simultaneously or alternately connecting said transmitter circuit and said receiver circuit to said antenna, selective means included in said receiver circuit comprising a plurality of circuits resonant at the carrier frequency and used in transmitting and a plurality of circuits resonant at the frequency of the incoming waves to be detected whereby the amount of energy of the transmitted frequency traversing the receiving circuit is reduced.

4. In a radio system for two-way communication comprising a transmitting circuit, a receiving circuit and an antenna, means for simultaneously connecting the transmitting and receiving circuits to the antenna, and means for alternately connecting the transmitting and receiving circuits to the antenna comprising a contact bar under the control of a relay and a push button.

5. In a radio system for two-way communication, means for selectively amplifying incoming waves for single detection comprising a plurality of amplifiers in series with a plurality of circuits resonant at the frequency of the incoming waves and a plurality of circuits resonant at the carrier frequency used in transmitting, one of each of said resonant circuits being included in the plate circuit of each amplifier.

6. In a radio system, an aerial, a transmitter circuit, a receiver circuit, an antenna switch adapted in one position to connect said transmitter circuit and said receiver circuit to said aerial, a loop circuit, and another switch adapted in one position to connect said loop circuit between said aerial and said receiving circuit through a path including a contact on said antenna switch, said other switch in said one position serving to close a circuit for holding said antenna switch in said one position and serving in another position to close a circuit whereby said antenna switch may be actuated under the control of an operator to disconnect said transmitter circuit from said aerial and to connect said receiver circuit thereto.

In witness whereof, I hereunto subscribe my name this 27th day of December A. D., 1923.

RAYMOND A. HEISING.
